UNITED STATES PATENT OFFICE.

HARRY T. ADAMS, OF NEW YORK, N. Y.

AWNING-LIFT.

SPECIFICATION forming part of Letters Patent No. 781,983, dated February 7, 1905.

Application filed January 26, 1904. Serial No. 190,522.

To all whom it may concern:

Be it known that I, HARRY T. ADAMS, a citizen of the United States, and a resident of the city of New York, borough of Brooklyn, in the county of Kings and State of New York, have invented a new and Improved Awning-Lift, of which the following is a full, clear, and exact description.

My invention relates to awnings, and admits of general use, but is peculiarly adapted for service in connection with awnings of the kind usually lifted at will by hand.

Reference is to be had to the accompanying drawings, forming a part of this specification, in which similar characters of reference indicate corresponding parts in all the figures.

Figure 1 is a vertical section taken upon the line 1 1 of Fig. 2 looking in the direction of the arrow and shows the awning as it would appear to a person within the building and looking outward. Fig. 2 is a vertical section upon the line 2 2 of Fig. 1 looking in the direction of the arrow. Fig. 3 is a fragmentary section somewhat similar to Fig. 2, but showing the awning as raised to its uppermost limit. Fig. 4 is a sectional detail showing the spring-roller 14 and its immediate connections; and Fig. 5 is a fragmentary elevation of one end of the spring-roller, showing the mounting thereof and connections therefor.

The window-frame is shown at 1 and the window-strip at 2. A number of hooks 3 are mounted within the top of the frame and are engaged by rings 4, worked into the front 5 of the awning. The sides 6 of the awning are of the usual construction. The awning-frame is shown at 7 and is preferably of metal, being rigidly mounted upon the movable rods 8^a, each provided with an eye 8, engaging an eye 9 on a longitudinal bracket 10 of the shape indicated and secured by fastenings 11 upon the window-frame. The pendant or flaps 12 13 of the awning are of the usual form. A spring-roller 14 is mounted across the top of the frame in the position shown, and upon it are partially wound a number of tapes 15, the upper or inner ends of these tapes being secured to the roller by means of fastenings 14^a and the lower ends being connected with the awning-frame 7. The spring-roller 14 is pro-

vided with a cavity 14^a, in which is mounted a spiral spring 14^b and a pawl 14^c, these parts being anchored within a ferrule 14^d. A flattened stem 14^e projects into a slot 2^a in the strip 2 and is thereby held against rotation. 55 The construction of this spring-roller *per se* is old and well known, being identical with that heretofore used for awnings. A halyard 16 is provided with a ring 17 and is partially wound upon the spring-roller 14 in the direction indicated in Fig. 2. A cord 18 is partially wound upon the spring-roller 14 at the end thereof, as shown at the left in Fig. 1. This cord passes through a pulley or block 19 at the bottom of the window-frame and thence passes angularly 60 outward, so as to connect with the awning-frame, as indicated more particularly in Figs. 1 and 2. The purpose of the pulley or block 19 and of the cord 18, running upon the same, is to hold the awning down, as against the attack of the wind, and this pulley and cord act in conjunction with the roller, so that when the awning is down the cord becomes taut. The window-panes are shown at 20 22, being mounted within the sashes 21 23 in the usual 70 manner. The spiral spring 14^b in the roller 14 is wound in such direction that it normally tends to roll up or elevate the tapes 15, so that the tension exerted by the hand upon the halyard 16 tends to increase the tension of this 75 spring. The awning is raised by the reaction of the spring and is lowered by the hand pulling against the reactive power of the spring.

My invention is used as follows: When it is desired to lower the awning, the halyard 16 or the ring 17 is grasped by the hand and drawn downward. This releases the spring-roller 14, which is normally held against rotation, as will be readily understood, in the same manner as the ordinary spring-roller 85 used in supporting window-shades. The halyard being drawn downward causes the eyes 9 to slide vertically downward upon the brackets 10 until they reach the bottoms thereof, whereupon the awning-frame swings outward 90 and downward until it assumes the position indicated in Figs. 1 and 2. The spring-roller automatically locks against back rotation, and the awning thereupon stays in the position indicated in Figs. 1 and 2. If now it be de- 100

sired to raise the awning, the halyard 16 or the ring 17 is grasped by the hand and given a slight jerk downward. This releases the spring-roller 14 and allows the same under 5 the tension of the spring 14^b to rotate in a contra-clockwise direction, as seen in Fig. 2, thereby winding up the tapes 15 and raising the halyard 16 and the ring 17. When the awning-frame is drawn upward into a substantially vertical position, the tension of the 10 spring being continued, the awning-frame is lifted bodily with reference to the window-frame, the eyes 9 sliding vertically upon the brackets 10 until the awning is completely 15 folded, as indicated in Fig. 3. It will be noted that in this figure the ring 17 is elevated to a little distance above its position indicated in Fig. 2. The awning is lifted by two successive movements, to wit: The awning-frame is first 20 raised angularly into a position approximately vertical and is then lifted bodily upward, so as to make the folds shown in the upper portion of Fig. 3. It will also be observed that the awning is self-raising, the power of the 25 hand being partially applied while the awning is being lowered. This enables a person to handle the awning with comparatively little exertion and also lessens the danger of an accident caused by the awning-frame being 30 dropped too suddenly into its lowermost position.

By the arrangement above described a comparatively heavy awning can be safely manipulated by a child.

35 Having thus described my invention, I claim as new and desire to secure by Letters Patent—

1. In an awning-lift, the combination of an awning-frame, a spring-roller for raising the same, said spring-roller being normally under 40 tension for the purpose, a longitudinal flexible member connected with said awning-frame and with said spring-roller for the purpose of raising said awning-frame by the tension of said roller, a pulley connected with the window-frame and disposed adjacent to the bottom of the awning, a flexible member connect-

ed with said awning-frame for the purpose of normally holding the same down, said flexible member engaging said pulley and passing upward from the same to the awning-roller, and 50 an additional flexible member partially wound upon said awning-roller and manipulated by hand.

2. In an awning-lift, the combination of a pair of longitudinal brackets vertically disposed upon opposite sides of a window-frame, an awning-lift slidably connected with said brackets and adapted to turn angularly with reference thereto, a spring-roller disposed adjacent to the upper part of said window-frame, 60 a canvas connected with said awning-frame and adapted to fold upon itself when said awning-frame is turned angularly, flexible members of longitudinal form extending from said roller to said awning-frame and engaging said 65 canvas so as to pull upward against the folds thereof after said awning-frame has been turned angularly, said flexible members thus raising said awning-frame to a comparatively high point relatively to said spring-roller. 70

3. In an awning-lift, the combination of a pair of longitudinal brackets disposed vertically upon opposite sides of a window-frame, an awning-frame connected with said brackets and free to turn angularly and also to move 75 bodily with reference to said brackets, a roller mounted upon said window-frame, flexible members connected with said awning-frame and with said roller, said flexible members being adapted to wind around said roller, means 80 for causing said roller to turn, and mechanism connected with said awning-frame and with said roller for normally holding said awning-frame in a predetermined position.

In testimony whereof I have signed my name 85 to this specification in the presence of two subscribing witnesses.

HARRY T. ADAMS.
